United States Patent Office

Des. 181,603
Patented Dec. 3, 1957

181,603

ORNAMENTAL METAL-WORK PANEL

Herbert E. Reid, Fort Worth, Tex., assignor to McKinley
Iron Works, Fort Worth, Tex., a partnership

Application May 23, 1957, Serial No. 46,298

Term of patent 14 years

(Cl. D54—2)

Fig. 1 is a side elevation of an ornamental metal-work panel embodying my new design;

Fig. 2 is a top view;

Fig. 3 is a sectional view taken on line 3—3 in Fig. 1.

I claim:

The ornamental design for an ornamental metal-work panel, as shown.
